—o—
A. PETZOLD.

RUG.

(No) 16,638.

Patented Apr. 20, 1886.

UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 16,638, dated April 20, 1886.

Application filed March 11, 1886. Serial No. 191,984. Term of patent 3½ years.

To all whom it may concern:

Be it known that I, ADOLPH PETZOLD, a citizen of the United States, and a resident of Philadelphia, Pennsylvania, have invented and produced a new and original Design for Rugs; of which the following is a specification, reference being had to the accompanying photographic illustration, to which reference is made.

10 In the illustration, A is a rectangular central panel ornamented by lilies B, surrounded by fern-like sprays C C. Above the upper and lower edges of this central panel are the stool-shaped figures D D, having rounded sides 15 and top. In the wide spaces between the end edges of the panel A and the end edges of the rug is the ornamental work E E, which consists especially of the two stalks G G—one in each end space—with the sprays H H and 20 leaves I I of the general form shown. The stool-shaped figures D D in the upper and lower borders contain figures resembling a half-wreath, each with a figure resembling in general form the *fleur-de-lis*. By "stool-shaped" I refer to the cone-shaped form of the 25 toad-stool.

The essential features of my design are the central rectangular panel, A, ornamented by lilies B B, the latter being surrounded by fern-like sprays C C, the end spaces between the 30 ends of the panel A and the two end edges of the rug being broader than the spaces between

the upper and lower edges of the panel and the upper and lower edges of the rug, as shown; also the border surrounding a large central 35 panel, A, being narrow above and below the same and ornamented with half-wreaths and *fleur-de-lis*-shaped figures, and the wide ends of the border being ornamented, as described, with the upright stalks G G, having sprays 40 H H and leaves I I.

What I claim as new is—

1. A design for rugs, consisting of a central rectangular panel, A, ornamented by lilies B B, the latter being surrounded by fern-like 45 sprays C C, the end spaces between the ends of the panel A and the two edges of the rug being broader than the spaces between the upper and lower edges of the panel and the upper and lower edges of the rug, substantially 50 as described and shown.

2. The border surrounding a large central panel, A, being narrow above and below the same, and ornamented with half-wreaths and *fleur-de-lis*-shaped figures, and the wide ends 55 of the border being ornamented, as described, with the upright stalks G G, having sprays H H and leaves I I, substantially as described and shown.

ADOLPH PETZOLD.
